(57) **CLAIM**

The ornamental design for a cleaner assembly, as shown and described.

DESCRIPTION

FIG. 1 is a front, top perspective view of a cleaner assembly showing our new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken line showing of various features of the cleaner assembly is for illustration purposes only and forms no part of the claimed design.
